KNITTING MACHINE

Julius Sirmay and Rudolph E. Zeruneith, Philadelphia, Pa.; said Sirmay assignor to The Ordnance Gauge Company, Philadelphia, Pa., a corporation of Pennsylvania

Application March 15, 1949, Serial No. 81,440

10 Claims. (Cl. 66—155)

Our present invention relates to knitting machines and more particularly to circular knitting machines of the two-bank type, that is, having a bank or bed of cylinder-needles and a bank or bed of dial-needles, and in which the resultant knitted structure or fabric may be alternately knitted off one or both sets of such needles, with some needles of either bank held inoperative at times and with the operative needles of two banks alternating or staggered in relation to each other in any desired sequence, for knitting predetermined areas, of any desired knitted structure, in patterned relation or sequence.

One of the objects of the present invention is a fully-automatic circular knitting machine of the general character indicated, in which successive sections (of tubular-knitted fabric), of any predetermined number of courses per section, may be knitted of different types of knit-formation, and in which the knit-formation may be changed between one section and another, automatically, and in which the knitted end-product may include a finished edge or self-edge, and another similarly knitted end-product may be immediately started, anew, so that successive knitted pieces, as, for instance, sweater-bodies, may be knitted, in succession, without any attention on the part of an operator to starting and stopping the successive knitted pieces or without any attention on the part of the operator to effect the necessary changes from one type of knitting to another type of knitting.

For instance, our present invention may be embodied in an 8-feed fully automatic interlock type of circular knitting machine, capable of knitting a seamless tubular body, as, for instance, a tubular knit sweater body of interlock knit-formation and a two-by-one or two-by-two sweater bottom with a self-edge.

Conventional phases or aspects of the machine will be described and shown only generally, and merely sufficiently to show the relationship of the various phases of our present invention to circular multi-feed interlock machines, generally.

One phase or aspect of our present invention is a novel automatic clutch and speed-change mechanism, so coordinated with and interrelated to the control mechanism, hereinafter referred to, that the speed of the knitting machine may be alternately changed from a high to a low speed and back to a high speed in timed relation to the successive positions of the control mechanism and in timed relation to the successive types of knitting operations, and by which clutch the machine may also be fully stopped, automatically, responsive to further controls (such as yarn-break controls) herein-after described.

Another aspect or phase of the present invention is a control mechanism including a timing-chain and a pattern-chain, which timing-chain and pattern-chain are both positively driven from the main drive of the machine, for moving both dial cams and cylinder-cams and for "racking" the cylinder head and needles (in relation to the dial-needles).

A further phase or aspect of the present invention is a certain novel stitch-control mechanism for automatically determining length or the tightness or looseness of the stitches.

A further aspect or phase of the present invention is a novel arrangement of cylinder sections and dial sections, and the construction of same, and the construction of the needle-actuating mechanism, by which the needles may be moved, inwardly or downwardly in a positive fashion, and by which the needle-cam controls (both of

2

the cylinder and of the dial) may be readily disconnected either for purposes of adjustment or for purposes of general disassembly.

Another phase or aspect of the present invention is a novel cam actuating mechanism intermediate the pattern-chain control mechanism and the needle cams.

A further phase or aspect of the present invention is a novel take-up mechanism whereby the tension on the fabric may be maintained more nearly uniform and yet one which will have a positive drive derived generally from the power shaft of the machine.

Another phase or aspect of the present invention is a certain novel yarn clamping and scissor mechanism.

Another phase or aspect of the present invention is a certain novel racking mechanism.

Other phases, aspects and features of the present invention will appear more fully from the accompanying drawings and the following description; reference being had to the accompanying claims to define the scope of our invention.

In the accompanying drawings, in which like reference characters indicate like parts,

Figure 1 represents a general perspective view of a knitting machine embodying the present invention; this perspective view not showing all the details, because the more detailed figures of the drawings (hereinafter referred to) are relied upon to show the details.

Figure 2 represents a perspective view of the clutch and speed-change mechanism.

Figure 3 represents a vertical cross-sectional view of the main drive shaft, clutch, and speed-change mechanism.

Figure 4 represents a fragmentary vertical cross-sectional view of the speed-change mechanism shown in Figure 3, with the clutch-control lever omitted, better to expose to view certain details of the speed-change mechanism.

Figure 5 represents a section on line 5—5, of Figure 4.

Figure 6 represents a perspective view of one of the two brake bands (114 and 115) of the speed-change and clutch mechanism.

Figure 7 represents a perspective view of the speed-change cam-shaft.

Figure 8 represents a vertical cross-sectional view (similar to Figures 3 and 4) of fragmentary portion of the speed-change mechanism, showing the clutch mechanism in the operative position.

Figure 9 represents a similar cross-sectional view of the clutch mechanism in the inoperative position.

Figure 10 represents an end view of the clutch mechanism, along line 10—10 of Figure 8.

Figure 11 represents a vertical cross-sectional view of the braking mechanism.

Figure 12 represents a section on line 12—12 of Figure 11.

Figure 13 represents a plan view generally on line 13—13 of Figure 11.

Figure 14 represents a perspective view of the electrical switch-box showing the connection of the kick-off lever to said power switch-box.

Figure 15 represents a perspective view of the pattern mechanism, timing mechanisms and racking mechanism.

Figure 16 represents a horizontal cross-sectional view of the cam shaft which operates the pattern mechanism, timing mechanism and racking mechanism (shown with its related elements).

Figure 17 represents the side elevational view of the shiftable main control-cam assembly (disposed on a fragmentary portion of the cam shaft shown in Figure 16).

Figure 18 represents a cross-sectional view on line 18—18 of Figure 17.

Figure 19 represents an end elevational view, along the line 19—19 of Figure 17, of one end of the main cam assembly shown in Figure 17.

Figure 20 represents a vertical cross-sectional view on line 20—20 of Figure 16, with the intermediate portion broken away, in order to better show the positive, speed-reducing intermittent-drive mechanism intermediate the main cam shaft and the timing shaft.

Figure 21 is an end elevational view of the intermittent-

drive mechanism of Figure 20, viewed generally on line 21—21 of Figure 20.

Figure 22 represents a perspective view of the shifting arm which forms a part of the double star-wheel speed-reducing intermittent-drive mechanism shown in Figure 20.

Figure 23 represents a perspective view of the instant-speed driving-and-backing wheel (of the mechanism of Figure 20) which intermittently drives first one and then both of the two star wheels (with the pinion of said driving-and-locking wheel not shown in this view).

Figure 24 represents a plan view of a portion of the mechanism shown in Figure 16, with parts omitted, and Figure 24 shows particularly the main cam assembly and showing the knock-down bar riding thereon.

Figure 25 represents a cross-sectional view generally along line 25—25 of Figure 24, showing the knock-down bar in lower position.

Figure 26 represents a cross-sectional view similar to that shown in Figure 25 with the knock-down bar shown in the upper position.

Figure 27 represents a fragmentary plan view of the mechanism shown in Figure 24, namely, the left side thereof, showing the connection of the cloth-take-up mechanism to the main cam shaft.

Figure 28 represents a side-elevational view, taken generally along line 28—28 of Figure 27, showing the eccentric-engaging fork and the upper end of the link or rod connected thereto; the lower end of which link rod extends down to the cloth-take-up mechanism.

Figure 29 represents a vertical cross-sectional view along the line 29—29 of Figure 15, showing the relationship of the pattern-chain on its control drum to the vertically slidable pattern-control rods and scissor-control rods.

Figure 30 represents a fragmentary plan view of three faces of the drum shown in Figure 29 and of one of the pairs of pivot rods which connect and form the links of the pattern-chain, with several pattern-controlling lugs shown fastened to said pair of pivot rods.

Figure 31 shows a perspective view of one of the pattern-control lugs.

Figure 32 represents a side elevational view, generally on line 32—32 of Figure 16, showing the cam-followers which actuate the pattern-chain drum (showing said cam-follower in relation to the main cam assembly).

Figure 33 is a plan view of the pattern-chain drum and its actuating mechanism, and is generally a plan view of the mechanism of Figure 15 and a portion of the mechanism of Figure 16, and this figure (33) shows the two cam-followers generally straddling the cam which actuates them, but with the cam in its left-most position when it is inoperatively disposed in relation to the cam-followers.

Figure 34 represents a side elevational view on line 34—34 of Figure 33.

Figure 35 represents a perspective view of the cam shifting mechanism, for shifting (upon the main cam-shaft) the main cam assembly (responsive to the timing-chain).

Figure 36 represents a side elevational view generally on line 36—36 of Figure 16, showing the timing chain and the cam-shifting fork assembly shown in Figure 35.

Figure 37 is a side elevational view generally along the line 37—37 of Figure 16, showing the cam-shifting fork in relation to the shifting-groove of the main cam assembly.

Figure 38 represents a vertical cross-sectional view on line 38—38 of Figure 36.

Figure 39 represents a perspective view of one of the actuating time lugs or links forming a part of the timing-chain.

Figure 40 represents a horizontal cross-sectional view taken through the axis of the main cam shaft and showing the extreme right hand end thereof with a part of the racking mechanism thereon.

Figure 41 represents a side-elevational view generally on line 41—41 of Figure 40, showing the "follower" yoke surrounding the racking cams.

Figure 42 represents a fragmentary plan view of the racking arm, the lower end of which (in Figure 42) is connected to the "follower" yoke of the racking mechanism.

Figure 43 represents a side-elevational view on line 43—43 of Figure 40, showing the intermittent drive from the main cam-shaft to the racking cam shaft.

Figure 44 represents a side-elevational view of the con-

trol stand with the upper ends of the vertical slidable control rods shown in relation thereto, and with the horizontal sliding fingers shown in relation thereto.

Figure 45 is a perspective view of the control stand with the vertical slidable rods omitted but with the projecting ends of the horizontal slidable fingers shown, to show the laterally staggered or laterally off-set relationship between the successive sliding fingers.

Figure 46 represents a front elevational view generally on line 46—46 of Figure 44, with the upper ends of the vertical sliding bars omitted or broken away.

Figure 47 represents a section on line 47—47 of Figure 46, on a larger scale, with the housing of the control-stand (in which the sliding fingers are mounted) omitted, to show the relationship of the horizontal sliding control fingers and the vertical control bars which actuate them.

Figure 48 represents an end-elevational view on line 48—48 of Figure 47 of the cylinder-control portion of the control stand.

Figure 49 represents a side-elevational view of the cylinder-control portion of the control-stand, taken generally on line 49—49 of Figure 47.

Figure 50 represents a plan view taken generally on line 50—50 of Figure 44, on a larger scale, showing the relationship of the dial-control fingers and two stitch-control fingers in relation to the vertical slide bars which actuate them (the control-stand housing in which they are slidably mounted being omitted).

Figure 51 represents an end-elevational view generally taken on line 51—51 of Figure 50.

Figure 52 represents a side-elevational view taken generally on line 52—52 of Figure 50.

Figure 53 represents a plan view generally on line 53—53 of Figure 44, showing the relationship of the scissor-control fingers and the vertical slide bars which actuate them (with the control-housing omitted); this figure being on substantially the same scale as Figures 47 to 52 inclusive.

Figure 54 is an end elevational view taken generally on line 54—54 of Figure 53.

Figure 55 represents a side-elevational view generally on line 55—55 of Figure 53.

Figure 56 represents a vertical cross-sectional view generally along line 56—56 of Figure 42.

Figure 57 represents a perspective view of the dual-track dial-stitch-control and dual-track cylinder-stitch control cam members.

Figure 58 represents a schematic diagram of the cam-track patterns of the cams of Figure 57.

Figure 59 represents a perspective view of the scissors and yarn-clamping mechanism.

Figure 60 represents a cross-sectional view generally along line 60—60 of Figure 59.

Figure 61 represents a cross-sectional view generally along line 60—60 of Figure 59, and similar to Figure 60, but showing the yarn-clamping and scissors blades in the lower position.

Figure 62 represents an exploded perspective view of the yarn-clamping and scissors mechanism of Figure 59.

Figure 63 represents a perspective view of one of the eight sections of the cylinder-ring which carries the cam tracks on its interior surface (shown in Figure 63), by means of which the cylinder-needles are actuated (eight similar sections forming the entire cylinder ring).

Figure 64 represents a cross-sectional view of the outer cylinder-ring in relation to the cylinder-needle-bank; taken generally on line 64—64 of Figure 63.

Figure 65 represents an elevational view of two cylinder-ring sections constituting a quarter of the circle (on a much smaller scale) showing one of the posts between these two sections, which post supports the revolving crow-foot.

Figure 66 represents a plan view of Figure 65.

Figure 67 represents a perspective view of one of the revolute tumblers (which in side elevation is shown in Figure 64).

Figure 68 represents the upper end of one of the cam-switch-operating plungers; showing the slot therein, which receives and is engaged by the eccentric pin of revolute tumbler shown in Figure 67.

Figure 69 represents a vertical cross-sectional view of the lower rotating crow-foot assembly and the (upper and lower) outer stationary frame members or posts and the stationary cylinder-needle-bed and the stationary sup-

ports therefor, and the revoluble cylinder-track assembly, and the revoluble dial-track.

Figure 70 represents a developed view of four of the sections of the cylinder-ring, constituting approximately one-half of the circle; showing the cam-track and the cam-switches.

Figure 71 is a fragmentary elevational view of the control-stand and of a portion of the revoluble cylinder-ring and dial-ring and yarn-change and scissors mechanism, showing relationship of the control-fingers to the rotatable cam-operating tumblers and to the yarn-tensioning star-wheel and to the yarn-change and scissor mechanism.

Figure 72 represents a plan view of one of the eight tumbler-supporting brackets and the connecting rods which connect the eccentric pins at the upper ends of the tumblers thereof with the cams in the corresponding one-eighth section of the dial-plate, in which the dial-tracks are disposed.

Figure 73 represents a side-elevational view of the bracket shown in Figure 72, with a portion of the dial-plate shown in section and with one of the cams therein shown in section.

Figure 74 represents a front-elevational view of the bracket taken generally along line 74—74 of Figure 72.

Figure 75 represents a plan view of the machine-bed in the area above the racking-mechanism, showing the relative positions of the racking elements disclosed in detail in Figures 40—43 inclusive.

Figure 76 represents a perspective view of one of the stitch-control-stands carried on the top of the cylinder-ring.

Figure 77 represents a side-elevational view of the same in a vertical plane, generally radial of the cylinder and dial, showing the relationship of the stitch-control-stand to the dial and to the cylinder.

Figure 78 represents a plan view of Figure 77.

Figure 79 represents a vertical cross-sectional view taken on line 79—79 of Figure 78.

Figure 80 represents a side-elevational view of the yarn-changing and scissor mechanism (also shown in perspective view in Figure 71).

Figure 81 represents a plan view of the same.

Figure 82 represents a section on line 82—82 of Figure 81.

Figure 83 represents a rear elevational view taken generally on line 83—83 of Figure 80.

Figure 84 represents a side-elevational view on line 84—84 of Figure 81.

Figure 85 represents a fragmentary plan view of the fabric take-up mechanism.

Figure 86 represents a side-elevational view generally on line 86—86 of Figure 85.

The novel drive of the present invention, including clutch and speed-change mechanism of the present invention, contemplates a single-speed, constant-speed, electric motor drive and two pulleys or pairs or multiples of pulleys of different diameters, each pulley or pair of pulleys being permanently connected to similarly diametered driven pulleys 100 and 101, the first pulley (100) for high-speed drive and the second pulley (101) for low-speed drive.

In the particular embodiment of the invention shown, each drive or pulley (100 and 101) is shown as a multiple type of V-belt drive or pulley, although it should be understood that these pulleys (100 and 101) may be any other suitable type of pulley or drive (such as, for instance, flat belts, sprocket type wheels-and-chains, etc.).

The high-speed pulley 100 is journaled directly upon the main shaft 102 through a sleeve-like hub 103 (upon which the pulley 100 is secured or which may be integral with the pulley 100) by means of anti-friction bearings 104 and 105, which bearings are schematically shown in Figure 3.

The low-speed pulley 101, is, in turn, journaled upon the sleeve-like hub 103 of the high-speed pulley 100, through similar anti-friction bearings 106 and 107, also schematically shown in Figure 3. The main shaft 102 is, in turn, journaled in bearing blocks 108 and 109, supported on the main frame 110 of the machine.

The hub of the low-speed pulley 101 has a cylindrical portion 111, similar to a brake-drum, and the hub 103 of the high-speed pulley 100 has a similar cylindrical portion 112 affixed thereto by means of the screws 113.

Each of these cylindrical members 111 and 112, is surrounded by a similar brake-band-like member 114 and 115, respectively, both housed in an outer speed-change housing 116, which, in turn, is keyed to the main shaft 102 by means of the key 117.

Each of the members 114 and 115 is split as at 118 and 119, and as at 120 and 121. At the split ends 120 and 121, similar but diametrically opposite radially projecting lugs 122 and 123 are formed (preferably integral with the split band). One lug of each pair of lugs (on each set of bands 114 and 115) as, for instance, the lug 123, is preferably provided with an adjustment screw 124, with a suitable lock nut 125 thereon, for obtaining an adjustment-setting of each band (114 and 115).

15 The speed-change housing 116 carries a clutch lever or arm 126, pivotally mounted at 127 within the upper chamber 128 provided for said lever or arm. The inner end of the arm 126 is bevelled as at 129, and this bevelled surface is juxtaposed to the ends of the adjustment-screws 124, so as to deflect the upper lugs 123 of both band-members 114 and 115, when the outer end 130 of the clutch arm 126 is raised and when the inner bevelled 129 end thereof depressed; such movement of the arm 126 serving to contract each band-member 114 and 115 a predetermined amount.

20 A clutch-actuating cone member 131 is slidably keyed to the main shaft 102, near its outer end, and is provided with a conical camming surface 132 and a cylindrical dwell 133, upon which the outer end 130 of the clutch-lever 126 is adapted to rest at all times; either resting on the conical camming surface 132 or on the bottom 134 of the generally V-shaped pulley-like clutch-actuating member 131, or to ride up on the cone-shaped cam-surface 132 thereof, or resting on the cylindrical dwell 133 thereof (according to the axial position in which the member 131 is placed by means of the clutch-control lever 135).

25 The clutch control lever 135 is pivoted at 136, upon the frame-extension 137. The clutch-control lever 135 is provided with an upper forked end 138 which straddles the groove 139 in the clutch-cone member 131 and which fork is revolvably interlocked with said clutch-cone member 131 by means of a pair of groove-runners or groove-rollers 140 pivoted to the opposite branches of the fork 138, upon pivots 141.

30 A helical compression spring 142 is interposed between the frame member 137 and the lower end 143 of the lever 135, so as always to urge the lever 135 in the direction indicated by the arrows 144, that is, counter-clockwise around its pivot 136 (in Figures 3, 8 and 9), thereby tending to set the clutch cone-member 132 in the "unclutched" or inoperative position as shown in Figure 9.

35 A hand-lever 145 is carried upon a transverse pivot 146, journaled in the frame member 137. To the other end of the pivot member 146 a bell-crank arm 147 is secured. To the upper arm 148 of the bell-crank 147 a link 149 is pivotally connected. The other end of said link 149 is pivotally connected at 150 to the lower end 00 of the lever 135. To the lower arm 151 of said bell-crank 147, the rod 152 is pivotally connected; the rod 152 being, in turn, pushed in the direction of the arrow 153 (Figures 3, 8, 9, 11 and 13) by the yarn-control knock-off mechanism so as to shut off the machine entirely, if a yarn breaks.

40 By throwing the hand-lever 145 from the position shown in Figure 9 to its position shown in Figure 8, the link 149 is pulled slightly to the left (in Figures 3 and 8) until it is thrown slightly beyond the dead center of the pivot 146, in which position the link is locked, automatically, in the operative position of the clutch, thereby to retain the clutch in its operative position, until either the lever 145 is thrown to the right again (as in Figure 9), either manually, or by the knock-off mechanism which swings the bell-crank 147 counterclockwise, whereupon the clutch is again rendered inoperative (as in Figure 9).

45 A speed-change cam-shaft 154 is provided, journaled in the lower part of the speed-change housing 116, parallel to the axis of the main drive shaft 102. The speed-change cam-shaft 154 has two pairs of "flats" 155 and 156, respectively; the flats of each pair being diametrically opposite to each other and parallel to each other while the flats of each of the different pairs are at 90° to each other. The pair of flats 155 is in alignment with the lower 50 lug 122 of the low-speed clutch-band 114, while the pair

of flats 156 is in alignment with the similar lug 122 of the high-speed clutch-band 115.

An annular locking groove 157 is provided in the shaft 154, to receive a lock-screw 158 so as to prevent the shaft 154 from moving axially (though permitting its free rotary motion).

The outer end of the cam-shaft 154 carries two pairs of turn-projections 159 and 160, respectively, the turn-projections of each pair being diametrically opposite to each other, while the turn-projections of one pair are spaced approximately 90° from the turn-projections of the other pair.

A speed-selector lever 161, pivoted at 162 to the frame member 137, has an upper selector finger 163. The lever 161 is constantly urged into its high-speed limiting position shown in solid lines in Figures 3 and 4, and is adapted to be shifted into its low-speed limiting position shown in dotted lines in Figure 4, by the pull of the solenoid or electro-magnet 165, through the connecting link 166 pivoted at 167 to the lower end of the selector-lever 161 and pivoted at 168 to the plunger or armature 169 of the electro-magnet 165 or to an extension thereof.

The electro-magnet 165 is, in turn, energized by a high link or timing-cam-link 275 (Figures 36 and 39) of the timing-chain 271, while throughout the passage of the low links 271-a (Figures 36 and 39) of the timing-chain 271, the electro-magnet remains inactive, so that the machine will be made to run at the high speed when the low links 271-a of the timing-chain pass beneath the roller 269, and will be made to run at a low speed when a high link 275 of the timing-chain 271 is beneath the roller 269 (see Figure 36).

The flats 155 and 156 of the speed-selector cam-shaft 154 and the diameter of the shaft 154 are so proportioned in relation to the clearance between clutch-bands 114 and 115 and their respective drums 111 and 112, that when the clutch bands 114 and 115 are partially contracted by the clutch arm 126, which is common to both bands 114 and 115, then, if the shaft 154 is turned so as to bring a "flat" against the corresponding lug 122 of one of the clutch-bands, that clutch-band will be "loose," while if the corresponding round or full-diameter portion (170 or 171) is turned into contact with the corresponding lug 122, the corresponding clutch-band (114 or 115) will be further contracted, sufficiently to cause it to tighten itself firmly upon the corresponding drum (111 or 112), and will thereby bring about the firm driving engagement between such drum (111 or 112) and the so-tightened band (114 or 115) and the revolute speed-change housing 116 which is connected to the main shaft 102.

By shifting the selector-lever 161 into either one of its two limiting positions (the high-speed position being shown in solid lines in Figure 4, while the low-speed position is shown in dotted lines in Figure 4), the selector-finger 163 thereof is brought in one of the two planes in which one of the two pairs of turn-lugs 159 and 160 lie. The finger 163 projects far enough to engage the turn-lugs, but clears the hub from which these lugs project. Thus, if the selector finger 163 is brought into either one of the two planes (of the lugs 159 and 160) it will act as a stationary abutment against which the projecting turn-lug strikes as the speed-change housing 116 revolves.

The turn-lugs (159 and 160) are so positioned (angularly) in respect to the corresponding flats 155 and 156, that one of the two lugs of the pair will project radially outwardly in respect to the axis of rotation of the housing 116 when a corresponding "flat" is juxtaposed to the corresponding lug 122, and so that both opposed turn-lugs (in the same plane) will be at the same distance from the center of rotation of the housing 116, when the full diameter portion (170 or 171) of the cam-shaft 154 is juxtaposed to the corresponding lug 122.

Thus, by moving the speed-selector finger 163 generally into the plane of either pair of turn-lugs 159 or 160, the speed-selector cam-shaft 154 will be turned 90° if the pair of turn-lugs into whose plane the selector finger is deflected are radially disposed in respect to the axis of rotation, and the selector finger 163 leaves the shaft 154 unaffected so long as it is in the plane of the turn-lugs which are generally tangentially disposed in respect to their orbit of rotation about the axis of shaft 102.

By placing the turn-lugs 159, more or less parallel to the flats 156 and by placing the turn-lugs 160 more or less parallel to the flats 155, the placing of the selector finger 163 into the plane of the turn-lugs 159 will cause

the clutch-band 115 to be tightened onto the drum 112 of the high-speed pulley 100, while if the speed-selector finger 163 is shifted into the plane of the turn-lugs 160, the band 115 will be loosened and the band 114 will be tightened onto the drum 111 of the low-speed pulley 101.

A pair of spring-pressed plungers 172 and 173, are slidably mounted in the lower part of the speed-change housing 116, to press against the flats 155 and 156, respectively, as the speed-selector cam-shaft 154 is rotated 90° from one position to the next position; these plungers (172 and 173) serving to prevent the shaft 154 from passing beyond its desired position by reason of the momentum of its rotational motion (imparted to it when one of the radially projecting turn-lugs 159 or 160 meets the stationary selector-finger 163 and is rotated thereby). The leaf-spring 174, supported at its center by the screw 175, is held in place with its two ends bearing against the outer ends of the plungers 172 and 173, so as yieldingly to urge these plungers against the corresponding "flats" of the speed-selector shaft 154, when such a flat is brought into alignment with a plunger (172 or 173).

The main drive shaft 102 (Figure 3) carries the spiral gear 190, through which the cam shaft 191 of the control mechanism is driven, through the driven spiral gear 192; one end of the cam shaft 191 being journaled in the bearing block 193 while its other end is journaled in the outer bearing 194, as well as in intermediate bearings 195 and 196 (Figure 16).

At the inner end of the main drive shaft 102 a beveled gear 197 is carried, beneath and enmeshed with the corresponding beveled ring gear 198, on the lower side of the top cam ring of the cylinder, designated by the numeral 199.

The main drive shaft 102 also carries a brake drum 200, as shown in Figures 3, 11 and 12, having an inner cylindrical braking surface, in which is mounted a split metallic brake-shoe ring 201, between the split and lugged end of which (as shown at 202), the flattened end 203 of the shaft 204 is disposed, so that a turning of this shaft will spread the end 202 of the split brake-drum ring 201 apart and force the brake-shoe ring 201 against the brake-drum and bring the machine to a quick stop. The shaft 204 carries the lever arm 205, at its outer end, which is tensioned by the helical tension spring 206, which spring has its other end suitably anchored in a stationary part of the frame, the spring tending normally to apply the brake. The lever arm 205 is held in its inoperative position, shown in Figure 12, by means of the plunger 207 slidably mounted in the bearing bracket 208 (Figure 12).

The other end of the plunger 207, is backed by the end 209 of the lever 210, pivoted at 211, and having a cam-follower 212 at its other end, in alignment with the cam surface 213 of the lever 214 which is pivoted at 215.

The lever 214 has its forked end 216 straddling the pin 217 carried by the actuating arm 218 of the knock-off box 219. The knock-off box 219 is a standard electro-magnetically operated device, in which the operating arm 218 is kept in the position shown in Figure 13 when it is set for operation, and in which the arm 218 is deflected into the position shown in dotted lines in Figure 13 in the off position. Thus, in the off position, the cam surface 213 moves to the right, in Figure 13, and permits the end 209 of the lever 210 to recede from the end of the plunger 207, so as to permit the lever 205, under the influence of the spring 206 to apply the brake shown in Figures 11 and 12.

When the end 216 of the lever arm 214 is moved to the right (in Figure 13) by the pin 217 of the switch handle 218, a lug 214-a, integrally fastened to the underside of the arm 214, engages an adjustable stop-member 152-a on the rod 152, moving the rod 152 in the direction of the arrow 153, causing the bellcrank arm 147 to rotate counter-clockwise (in Figures 3, 8 and 9) so as to disengage the clutch-mechanism, as heretofore described.

The control mechanism is shown in Figures 15 to 43 inclusive, and consists of a selector chain mechanism having a control chain with adjustable control lugs or control jacks, which chain is adapted to be advanced, periodically, a link at a time, and is adapted to be reciprocated up and down beneath a set of slideable cam-control levers and selectively to engage the same, and an actuating mechanism for said selector-chain mecha-

nism for reciprocating the same during certain intervals and rendering it inoperative during other intervals, and also for advancing the chain, a link at a time, responsive to a timing chain, a timing mechanism of which said timing chain is a part, for timing the actuating mechanism, and a racking mechanism controlled by a control-jack upon the selector-chain.

The control mechanism that contains the main control shaft 191 and a secondary timing shaft 221, suitably journaled therein, is supported by the frame members 222 and 223.

On the main control shaft 191, a selector-chain control-cam 224 is slidably mounted, keyed thereto, however, so as to be driven by the shaft 191.

The selector-chain controlling and actuating cam-drum, as shown particularly in Figure 17, includes a selector-chain actuating-cam or selector-eccentric 225, and the selector-lever return-cam 226, and the shifting cam 227. These three sections (225, 226 and 227) of the cam-drum 224 are either formed integrally with each other or are keyed and fastened together, so that there can be no relative rotation between them nor any relative axial movement between them, namely, so that they will all move together, in unison, both rotationally and axially.

A lifting-arm 228, as shown more particularly in Figure 32, is pivoted at 229 and has, at its outer end 230, a pivot pin 231, to which a link 232 is connected, in which the selector-drum-shaft 233 is pivoted. As shown more particularly in Figure 33, the lifting-arm is forked at its outer end, with the two branches thereof separately designated (in Figure 33) as 230-a and 230-b. Similarly, there are a pair of links 232, which in Figure 33 are separately designated as 232-a and 232-b, respectively, each carrying one end of the selector-drum-shaft 233.

The lifting-arm 228 carries a pair of cam-follower rollers 234 and 235, which are in alignment with each other and which are spaced from each other at a distance such as will accommodate the maximum transverse dimension of the cam or selector-eccentric 225. The cam drum 224 has a lateral or axial movement of an amount indicated by the solid and dotted views, respectively, of the cam 225 in Figure 24. In its position shown in dotted lines in Figure 24, the cam 225 is in its operative position, while in the position shown in solid lines, in Figure 24, the cam 225 is in its inoperative position. The mechanism for shifting the cam-drum 224 for the purpose of moving the cam 225 thereof either into its operative or into its inoperative position, is shown more particularly in Figures 16 and 35 to 38 inclusive, and will be described more in detail hereinafter.

The selector-chain drum 236 is preferably octagonal in cross-section, as shown particularly in Figure 29 (although it can be of any other polygonal cross-section) so that the flat faces 237 thereof will form flat bearing surfaces and supports for the flat bottom surfaces 238 of the base-member 239-a of the selector-jacks or selector-lugs 239. The selector-lugs 239 are adjustably fastened to the pivot rods 240 of the selector-chain 241 with the upstanding knob or abutment 239-b extending above the base-member 239-a between the pivot-rods 240 and with a recess 239-c defined by a flange 239-d adjacent one pivot-rod 240, and another recess 239-e in juxtaposition to another of said pivot-rods 240, and with a locking-screw 239-f extending through a hole 239-g in said flange and also into a hole 239-h in said knob, detachably to lock said selector-jack 239 to said pivot-rods 240. The shaft 233 of the selector-drum 236 passes through a pair of guide blocks 242-a and 242-b, respectively, which are slidably mounted in the vertical slots or guide-ways 243-a and 243-b, respectively, in the selector frame members 244-a and 244-b, respectively, thereby to guide the selector drum 236 in a straight vertical linear path, in its up and down motion when raised and lowered by the arm 228. At each end of the selector drum 236, there is a sprocket wheel 245, on which the opposite ends of the sprocket chain rods 240 run, intermediate the links 246 thereof (Figure 30).

A ratchet wheel 247 is secured to one end of the selector-drum shaft 233, and is adapted to be engaged by the pawl 248, when the shaft 233 and drum 236 are lowered by the arm 228 (Figures 32 and 33). The pawl 248 is yieldably urged toward the ratchet wheel 247, by

the helical torsion spring 249, the inner end of which is held in position in a slot in the post 250 upon which it is supported, while the outer end 251 of which extends outwardly and then is bent at a right angle, in back of the pawl 248, so as to urge it toward the ratchet wheel 247. The spacing of the teeth of the ratchet wheel 247 is such that upon downward motion of the selector-drum 236, the selector-drum will be turned one-eighth of a revolution, so as to move the selector chain forward by one link or one step, so as to present the next set of selector-jacks or selector-lugs 239 to the lower ends of the vertical slotted mounted cam-control levers or bars 252. The left link 232-a may be extended upwardly as at 232-c (see Fig. 32) for carrying a locking or non-return pawl 253, suitably tensioned by the spring 254 toward the ratchet wheel 247, so that it will fall directly behind each tooth, as it is advanced, and prevent the ratchet wheel from turning backward or prevent the selector drum 236 from moving backward, after it has been advanced by riding downwardly past and in contact with the pawl 248.

The entire cam drum 224 is shifted, to and fro, that is, from left to right and from right to left, by means of the shifting cam 227 and the forked shifting yoke 255 (shown particularly in Figure 35) carried upon and keyed to the pivot shaft 256. The forked yoke 255 carries a pair of opposed cam-follower pins 257 and 258, disposed generally radially of and straddling the shifting cam 227, with the axes of said pins 257 and 258 disposed in offset planes at a right angle to the axis of the shaft 191, as shown more particularly in Figure 16.

The shifting cam 227 consists essentially of a pair of offset flanges 259 and 260, each extending around the circumference slightly less than 180°, and being connected by the intervening connecting camming portions 261 and 262 spaced apart at 180° from each other. One of these is shown in solid lines in Figure 17, while the other is shown in dotted lines in Figure 17. When the yoke 255 is deflected downwardly, so that the pin 258 thereof enters the cam 227, the cam 227 and the entire cam drum 224 are shifted in the leftward direction, because the pin 258 engaged the camming surface 262 and shifts such surface until the pin 258 passes the right-hand face 263 of the flange 259. Whenever the yoke 255 is shifted upwardly or deflected upwardly, then the pin 257 thereof enters the cam 227, so that upon the continued rotation of said cam, the camming surface 261 passes the pin 257 and causes the cam 227 and the whole cam drum 224 to shift to the right until the pin 257 arrives adjacent to the left-hand face 264 of the flange 260. A helical tension spring 265, having one end thereof fastened to a spring-anchorage pin 266, on top of the yoke 255, and having the other end thereof fastened to the stationary spring anchorage 267, constantly urges the yoke 255 into its downwardly-deflected position, namely, into that position in which the yoke 255 will shift the cam-drum 224 into its leftmost position, namely, that position which is shown in Figure 24, in which the selector-lifting cam 225 is in the inoperative position, which is the position in which the cam-drum 224 is most of the time.

To the outer end of the pivot shaft 256, which carries the shifting yoke 255, a rocker arm 268 is secured, having a cam-follower roller 269 on its lower arm 270, in vertical alignment with the timing chain 271, and having an upper arm 272 which is adapted to press against the knob, button or plunger 273 of the micro-switch 274 (or any other suitable electrical switch 274) when the pivot shaft 256 is rotated in a clockwise direction (as shown in Figure 36) by such amount as corresponds to the lifting of the follower roller 269 by a timing-cam lug 275, which is carried at any desired interval, by the timing chain 271.

The timing chain 271 is carried by a sprocket wheel 276, which, in turn, is keyed to the right-hand end of the timing shaft 221. Thus, by placing one of the detachable timing-cam lugs 275 at any suitable or desired intervals upon the chain 271, the shifting yoke 255 may be raised, so as to bring the pin 257 thereof into the cam 227 and thereby shifting the selector-cam 225 into its operative position shown in dotted lines in Figure 24, and thereby to advance the selector chain 241 by one position with each revolution of the control shaft 191, so

long as a timing-cam lug 275 remains beneath the lower cam 269. However, when the sprocket wheel 276 is advanced another step (in a counterclockwise direction as respects Figure 36) so as to remove the timing-cam lug 275 from beneath the cam follower roller 269, then the pivot shaft 256 is deflected in a counterclockwise direction (with respect to Figure 36) by means of the spring 265, until it reaches the position determined by the adjustable screw-stop 277, against the lower end of which the arm 278 of the rocker arm 268 is adapted to bear in the inoperative position thereof. The switch 274 is connected electrically with the speed-change controlling electromagnet 165 shown in Figures 3 and 4, so as to cause the drive to shift into its low-speed position whenever a timing-cam lug 275 is beneath the cam-follower roller 269, so that the knitting will operate at the slower of its two operating speeds whenever a change in any of the controls is effected (namely, whenever the needle-operating or jack-operating cam-switches in either the cylinder cam-track or in the dial cam-track are being operated, or whenever any of the yarn-controls are operated).

The knock-down cam 226 is of sufficient axial width to remain at all times in operative alignment with the cam-follower roller 279 carried by the extension-arm 280 of the knock-down plate or return 281 which is pivoted at 282. The plate 281 carries a blade 283 extending across the entire width of the entire bank of vertical slidably selector levers or bars 252, at the back thereof, as shown particularly in Figures 25 and 26, and is in alignment with the return-projections 284 thereof. Therefore, with each revolution of the control-shaft 191, the return-blade 283 is deflected downwardly so as positively to return to their downward starting position all of the vertical slidable selector bars 252, which may have been raised into an upper operative position by a selector-jack 239. As the selector-drum 236 is not raised with each revolution of the control cam 191, the return-blade 283 may be moved downwardly without any return lugs 284 to engage, and in such event, the return blade 283, will just move down and up again idly.

A helical tension spring 285 has its lower end anchored to the plate 281, while its upper end is anchored to a stationary spring anchorage 286, thereby to lift the plate 281 and the return-blade 283 into its upward position, and to keep it there out of the way of the return-projections 284, except for the short interval during which the high dwell 287 of the return cam on return-eccentric 226 is in the upper position. The dwell 287 is so disposed, angularly, in relation to the high dwell 288 of the selector cam 225, that the blade 283 will move down immediately after the selector drum 236 has moved down.

The timing shaft 221 is driven intermittently, $\frac{1}{24}$ of a revolution at a time, for each 24 revolutions of the main control shaft 191, by means of the mechanism shown more particularly in Figures 20 to 23 inclusive. This time-shaft driving mechanism consists of the following:

Gear pinion 290, is keyed to the main control shaft 191, as shown particularly in Figure 20 and Figure 21, and is in constant mesh with a pinion of like diameter and the equal number of teeth 291, idly journaled or pivoted and axially slidably upon the stationary pivot member 292 which is rigidly carried by its end 293 in the frame member 222 (Figure 20). Immediately adjacent to the gear or pinion 291, is the continuous cylindrical Geneva-stop member 295. Immediately adjacent to the cylindrical member 295 is the cylindrical member 296 having the flat portion 297, in juxtaposition to the single gear-propelling pin or tooth member 298. The pin 298 is carried by the right hand face of the shifting cam 299, which is integral with or is rigidly secured to the members 296, 295 and the gear 291, so that these members will rotate and shift in unison.

The shifting cam contains a cam groove 309, which is wider through most of its circumference, and is narrowed through a small part of its circumference at 301. A lever 302 is pivoted upon the vertical pivot pin 303 (at the lower end thereof), and carries a cam-follower roller 304 beneath its outer end and a similar cam-follower roller 305 above its outer end. The upper cam-follower roller 305 permanently rides in the cam-groove 300 and is of a diameter just to clear past the narrow portion 301

of said cam-groove. The lower cam-follower roller 304 rides constantly in a cam-groove 306 in the cam-member 307 which is idly journaled upon the timing-shaft 221, as shown particularly in Figures 20, 21 and 22.

The cam-groove 306 has one off-set 308 therein, in a right hand direction in relation to Figure 20, so that once in every revolution of the cam-member 307, the lever 302 will be deflected in a right-hand direction, in respect to Figure 20, thereby moving the cam-follower rollers 304 and 305 in a right-hand direction in relation to Figure 20. The length of the right-hand dwell 308 in the cam-groove 306 is such as to cause the upper cam-follower roller 305 to move the members 295, 296 and 299 in a right-hand direction, while the cam-follower 305 is in the wide part of the cam-groove 300. The dwell 308 sets the roller 305 into its camming position while the roller 305 is in the wide part of the cam-groove 300, so as to be in readiness and in position to shift the cam-member 299 (and with it the members 296 and 295), when the cam-member 299 turns to the position where the narrow portion of the groove 301 is in operative alignment with the roller 305.

The cam member 307 carries, fixedly secured thereto, a slotted wheel 308, having 24 slots 309 therein, with the cylindrical portions intervening the slots, being concavely curved as at 310, and with the circular curvature having a radius substantially equal to the radius of the cylindrical portions 296 and 295. The corners or junctures intermediate the side walls of the slots 309 and the concave portions 310, are slightly beveled as at 311.

A similar slotted wheel 312 is carried by a hub member 313, which is keyed to the timing shaft 221 as shown particularly in Figure 20. With each revolution of the gear 291 (and hence with each revolution of the main control shaft 191) the pin 298 enters the next slot 309 in the slotted idler wheel 308 while the flat portion 297 of the cylindrical locking member 296 is facing the wheel 308, so as to permit the wheel 308 to be rotated by the engagement of the pin 298 in one of the slots 309. As the pin 298 withdraws from the slot 309, after it has moved the wheel 308 the distance of one tooth 314, the cylindrical locking portion 296 revolves into place in the concavely curved portion intervening the slot 309 (which has just been left behind by the pin 298) and the next such slot, thereby to lock the wheel 308 against rotation until the pin enters the next slot. By this means, the idler wheel 308 is revolved one complete revolution for every 24 revolutions of the main control shaft 191. In every such revolution of the idler wheel 308 and hence in every 24 revolutions of the main control shaft 191, the cam-groove 306 of the cam 307 (to which the idler wheel 308 is affixed) presents its deflecting dwell 308 to the lower cam-follower 304 carried by the lever 302, and deflects said lever to the right (viewed as in Figure 20) and thus positions the upper cam-follower 305 carried by said lever 302 for engaging the camming surface 315 of the cam-member 299 (see Figure 23) thereby to shift the pin 298 and the locking member 296 and the release-clearing "flat" 297 to the right, a distance approximately equal or slightly in excess of the thickness or width of the second keyed slotted wheel 312, so that upon the next revolution of the gear 291 and of the control shaft 191 the keyed tooth or slotted wheel 312 will be rotated $\frac{1}{24}$ of a revolution (along with the similar $\frac{1}{24}$ rotation of the idler wheel 308). By this means the timing sprocket wheel 276 will be revolved $\frac{1}{24}$ of a revolution with each 24 revolutions of the control shaft 191, or will be revolved one full revolution for each 576 revolutions of the control shaft 191.

This indexing of the timing sprocket wheel 276 and hence of the timing chain 271 may be in any other desired ratio in relation to the revolutions of the main control shaft 191, according to the number of shifting dwells 308 provided in the cam-groove 306. Thus, two such shifting dwells 308 may be provided 180 degrees apart or three such shifting dwells 308 may be provided 120 degrees apart, according to how close a control is desired.

In this manner with a single shifting dwell 308, in the cam-groove 306, the cam-member 275 of the timing chain 271, when brought beneath the cam-follower roller 269, will stay there through 24 revolutions of the control shaft 191 and hence through three revolutions of the knitting head. This allows for 24 control operations or selector operations while a timing cam 275 is in an operative position.

During such 24 movements of the selector drum 236

and selector chain 241, any of the needle controls and thread controls may be operated to effect any desired change of stitch or any desired dropping or activation of threads or any desired immobilization or activation of the knitting needles, by placing a suitable number of selector jacks or selector lugs 239 on the selector chain 241, at the desired position on the chains for each of the vertical slideable selector levers 252.

By the selector-camming mechanism shown particularly in Figures 16 to 19, 24 to 26 and 32 to 38, a positive selector action is obtained as well as a positive return of the elevated selector bars, after they have been raised.

By the timing mechanism shown in Figures 20 to 23 and 35 to 38, the timing of the selector-actuating cam is positively advanced as is also positively locked after each advance, so that it can never get out of the desired or preset timed relation.

Thus, as the slotted or toothed wheel 312 of the camming mechanism is locked by the shifting of the cylindrical locking portion 295 into the next concave portion 310 of such wheel, after each advancement, by one tooth, the entire timing mechanism is always kept locked, except when being advanced by one step or one tooth by the pin 298.

The racking mechanism is shown particularly in Figures 15 and 40 to 43 inclusive.

The outer end or the right-hand end of the main cam shaft or main control shaft 191 of the knitting machine, is journaled, in the frame member 194, in the roller bearing 315.

Near this same end of the cam shaft 191, near the bearing 315, a driving and locking drum 316 is slidably mounted and keyed thereto so as to rotate therewith. At one end of the drum 316 there is a groove 317, in which rides the pin 318 of the shifting bell crank lever 319, which lever is pivoted at 320 to the main bed 321 of the knitting machine.

The other arm 322 of the bell crank lever 319 carries a pin 323, which rides in the slot or clearance between the two lugs or rearward projections 324 and 325, carried by and forming a part of the right-most selector bar 326 (see Figure 15) and (see Figure 40).

By placing a selector jack or selector lug 239 on the proper link of the selector chain 241, in alignment with the right-most selector bar 326, the driving and locking cylinder 316 is shifted from its position shown in Figure 40 to a position to the left thereof, so as to shift the full-cylindrical locking portion 327 out of alignment with or out of registration with the slotted star-wheel 328 and to bring the driving portion 329 of the drum 316 and the driving pin 330 carried by the flange 331 of said drum 316, into alignment or registration with the slotted star-wheel 328. Thus, when the right-most selector bar 326 is raised, the driving and locking drum 316 is shifted leftward in Figure 40 and the slotted wheel or star-wheel 328 is unlocked momentarily by the concaved peripheral portion 329 and the pin 330 entering a slot 332, and advancing the wheel 328 a number of degrees equal to the angular distance between successive slots. The wheel 328 is keyed to the racking shaft 333, journaled in the housing member or bracket 194, and to the other end of said racking shaft 333, a pair of racking cams 334 and 335 are keyed.

The cams 334 and 335 are surrounded by a racking yoke 336, pivoted upon the pivot pin 337 which is rigidly carried by a frame-extension 338, which extends from the frame member 194. The top of the racking yoke 336 carries a pivot support 339, to which the forked end 340 of the adjustable link 341 is pivotally connected by means of the pivot pin 342. The adjustment of link 341 is accomplished by means of the adjusting sleeve 343, which is threaded internally and externally (one of its threads being right-handed and the other left-handed) so that by turning the sleeve 343 the link extension 344 is adjusted, lengthwise, of the main link body 341. The link extension 344 is journaled to a pivot pin 345, through a ball and socket journal 346 (as shown more particularly in Figure 41).

The pivot pin 345 is carried by a slide 347, which is slidably mounted in one arm 348 of the bell crank lever 349 which is pivoted upon the pivot pin 350 between the stationary frame member 321 and the pivot bracket 352 extending downwardly from the main frame member 321, to give the pivot pin 350 support at both ends thereof. 80 85

The other arm 353 of the bell crank lever 349 is offset as shown particularly in Figure 42, and has its end bifurcated as at 354-a and 354-b, and between these forked ends a pin-pivoting guide block 355 is slidably mounted in the manner shown in Figure 42. The pivot pin 356 is journaled in the guide block 355; the upper end of said pivot pin 356 being firmly secured in and preferably riveted in the ring 357 which supports the cylinder needle bed 358; the ring 357 being carried by the frame member 321 in the manner indicated in Figure 56.

The axes of the pivotal centers of the pivot pins 356 and 350 are on a radius-line passing through the center of the head of the knitting machine. Thus, by rocking the rocker arm 349, slightly, in either direction, about its pivotal support 350, the ring 357 and hence the cylinder needle bed 358 carried thereby are racked correspondingly, in either direction.

The slide 347 is held in its guide channel 359 in the arm 348 by a headed screw 360, the shank of which passes through a slot 361 in the arm 348, and is threaded into the slide 347. An adjustment screw-post 362 is fixedly screwed in the arm 348, in the manner shown in Figures 41 and 42, and has a knurled or other suitable nut 363 thereon, which enters a slot or recess 364 in the slide bar 347, so that by temporarily loosening the bolt or screw 360, the slide 347 and hence the pivot 345 of the link 341 and 344 may be moved closer to or further away from the pivot 350 of the rocker arm 349; the bolt or screw 360 again tightened when the desired pivotal setting has been accomplished. 20 25 30 35

By this means the effective length of the arm 348 of the rocker 349 can be varied so as to vary the amount of racking which will correspond to any given throw of the cams 334 or 335. Thus, the same cam or pair of cams may be caused to rack the cylinder needle bed in varying ratio to the rise and fall of the cam by changing the effective length of the arm 348 of the rocker 349, in the manner just described.

The cams 334 and 335 are rigidly fixedly in relation to each other and both keyed to the shaft 333, and, in the particular embodiment of the present invention shown, each has six positions corresponding to the six positions of the star wheel 328, although the number of positions can be increased or decreased, as may be desired. Thus, instead of having six positions, the wheel 328 may be provided with eight slots or eight positions and the cams 334 and 335, in turn, being then provided with eight positions. The positions (whether four, six or eight or any other number) are preferably equally-distantly spaced from each other, that is, with an equal angle between two successive positions. Thus, in the 6-position cams, the positions would be 60° apart. In the 8-position cams, they would be 45° apart, and so on.

Each of the two cams 334 and 335 serves a dual function, namely, in racking the cylinder bed in one direction, one cam will be what may be regarded as the "driving" cam, one "position" of which is determinative of the racking effect, while the other cam then acts as a slack-eliminator or locking cam. When racking the cylinder bed in the opposite direction, the reverse takes place and the latter cam becomes the driving cam and the former cam becomes the slack-eliminator or locking cam. This is accomplished by the follower rollers 365 and 366 which are in registration or in alignment with the cams 334 and 335, respectively, and which are at substantially diametrically opposed positions in respect to the axis of the racking shaft 333; the distance between their closest peripheral points being set to substantially equal the opposite radii of the cams 334 and 335. The cams 334 and 335 are, in turn, so shaped that their opposed radii, at least in their various "positions" in which such radii are held locked by the star wheel and control mechanism shown in Figure 43, always add up to the same additive dimension, so that while the follower 365 is on a high point or "position" of the cam 334, the follower 366 will be on a correspondingly low "position" of the cam 335.

In a pair of 6-position cams, each cam can be provided, for example, with two zero positions, three half-needle positions, and one one-and-a-half-needle position. The first position of one cam is diametrically opposite to the fourth position of the other cam. The second position of the one cam is diametrically opposite to the fifth position of the other cam. The third position of the one cam is diametrically opposite to the sixth position of the other cam. Thus, by way of example, if the first position of a

cam will set the cylinder needle bank with its needles in direct and full alignment with the dial needles, as, for knitting an interlock or a 2 by 2 stitch (with alternate needles or alternate pairs of needles in each bank inoperative), then the second position of the same cam would have a change of radius in respect to the first position by an amount which would correspond generally (subject to the adjustment of the bell crank arm 348 in the manner hereinabove described) to half of the distance between needles or "a half a needle." The third "position" of the same cam would have its radius differ from the second position radius by an amount corresponding to "one needle" and hence different from the first position by one-and-a-half needles. The fourth position of the same cam would then be the same as its second position, that is, of the same radius, while the fifth and sixth positions of the same cam would have the same radii as the first and second positions, respectively. The other cam would then have similar positions with its radii varying similarly, but 180° from the positions of the cams, so that (as stated before) the radii of the two cams in their positions of 180° apart will always add up to the same dimension, so that one cam becomes the rack-determining cam, the other cam locks the cylinder bed in the so-racked position and prevents any possibility of any backward movement of the cylinder bed from its racked position determined by the cam which (in that direction of racking) is the rack-determining cam.

The radii of the various positions of these two racking cams may be varied by substitution of differently-shaped cams. Thus, instead of having the first position as above indicated, and instead of having the successive positions differing from the first position by a half-needle and a one-and-a-half-needle and then again a half-needle, and so on, the amount of racking per "position" can be increased. Thus, the difference between the first and second positions of the cam may be more than a half-needle, as for instance, a one-and-a-half needle or three needles, or whatever amount of racking may be desired for the particular knitting desired. Thus, by making up different matched pairs of racking cams 334 and 335, and by merely taking off one pair and replacing it with another pair, the knitting machine may be adapted for a different knitted fabric. The same holds true whether the cams are 6-position cams or 4-position cams or 8-position cams or any other number of position cams.

The cam-followers 365 and 366 are rotatably carried in corresponding guides 367 and 368, respectively, pivoted thereto by means of pins 369 and 370. The guides 367 and 368, are, in turn, slidably mounted in guideways 371 and 372, in the nature of channels, and are locked in position by the screws or bolts 373 and 374, which pass through elongated openings in the slidable members 367 and 368, and are threaded into the body of the yoke 336. Adjustment screws 375 and 376, having knurled heads engaging corresponding slots 377 and 378, in the slides 367 and 368, are threaded into the body of the yoke 336, in the manner indicated in Figure 41, so that the positions of the slides 367 and 368, and hence of the follower-rolls 365 and 366 may be more finely adjusted (while the set screws 373 and 374 are temporarily loosened). By this means, the follower-rolls 365 and 366 are adjusted to the cams, so that they will act, alternately, as the rack-determining adjustment and the locking adjustment, without any appreciable "slack" between the rolls 365 and 366 and the corresponding cams when set to any of their "positions."

In Figures 44 to 55 inclusive and Figure 71, the control-box is shown which contains and slidably guides and retains the slidably mounted horizontal control cams.

Thus, in Figure 45, the control-box with the end thereof which faces the vertical selector bars or slides is shown in perspective view; showing the ends of the cam bars which are engaged by the vertical selector bars 252; said selector bars being guided in the slots 380 of the guide yoke 381.

The lower section of the control-box, designated generally by the numeral 382 contains the cylinder-controlling cams and cam-bars 383, while above it are the stitch-controlling cams and cam-bars 384, while above these, are the dial control cams and cam-bars 385.

Above these is the cam-bar 386, the front end of which terminates in the scissor-control cam 387, and in the cam 388 which releases the yarn-change finger, namely, such yarn-change finger or fingers as have previously been set

into the knitting position by one of the three or more yarn-change setting control-cams 389.

The dial cams as well as the cylinder cams (which actuate the needles and jacks), are set into their desired camming position or into their inoperative positions, as the case may be, through a series of tumblers 390, one of which is shown in perspective view in Figure 67, consisting of a generally cylindrical body having intervening groove 391 therein, for the reception of the spring loaded retainer ball 392. In the groove 391 there are two diametrically opposite recesses; a slight enlargement or indentation 393, into which the ball 392 is adapted to engage, for yieldably retaining the tumbler 390 in either of its two positions, 180 degrees apart. The ball 392 is pressed into the groove 391 (and the recesses 393) by a spring 393-a, on which the tension can be adjusted by movement of the retaining screw-plug 393-b.

Each tumbler has, at its outer end, a pair of control pins 394, 180 degrees apart, and has at its other end 20 the cam-actuating pin 395, disposed eccentrically in respect to the axis of the tumbler.

The tumblers 390 which actuate or control the cam-posts 396 of the cylinder-cam box 397, and through such posts control the cylinder cams mounted upon and carried by the posts, are disposed horizontally (as shown particularly in Figure 64) in the cylinder-cam box sections 397, being preferably mounted in roller bearings as shown particularly in Figure 64. The eccentric pin 395 engages in a transverse slot 398 disposed at a suitable point along the length of the cam post 396, adjacent to which slot is a flat 399, against which the corresponding end of the tumbler 390 may bear or which clears the end of the tumbler. By rotating the tumbler 390 180 degrees, the cam-post 396 is raised or lowered, as the case may be, into either of its two limiting positions, thereby raising or lowering the corresponding cams carried thereby. The ball-receiving recesses 393 are so disposed, as to retain the tumbler 390 in the two limiting positions of the cam post 396.

40 The pins 394, are, in turn, so disposed that they are in alignment with a corresponding cam bar 383, so that when the corresponding cam bar 383 is in its extended position (as effectuated by the selector chain 241 and the corresponding vertical selector bar 252 with a selector 45 jack suitably placed upon the chain), it will thereby turn the tumbler 393 into a position 180 degrees from its former position.

One, two or three cam bars 383 are provided in operative alignment with or at the level of each of the tumblers 390, or more particularly at the level of the pin 394 thereof which is nearest the control box 382 as the cam box 397 approaches the control box. The tumbler 390 corresponding to certain of the control cams may only have a single cam bar 383, while two or three cam bars 55 may be provided at the level of other of the tumblers, according to the cams to which they are connected.

Thus, for instance, the tumbler connected to the cam post 396-a, in Figure 63, which carries the long butt cams 590 and 591, would have two cam bars 383 in the cam box, at two different positions, while the tumbler which is connected to the cam post 396-b in Figure 63, which carries the short butt cam 592, would have three cam bars 383 in the control box. As the two or more cam bars 383, in the control box 382, at the level of any particular tumbler are spaced angularly from each other in respect to the axis of rotation of the head of the machine, they will cause the tumbler to revolve 180 degrees at a slightly different point in the rotary orbit of the cam box, and thus effect an upward or downward shift in the corresponding needle-actuating cams at a slightly advanced or slightly retarded point in the cycle or in the rotary orbit of the cam box. The tumbler 390-c, in Figure 63, which is connected to the jack-operating cam-post 396-c or 396-c¹, has but a single cam bar in the control box, because the actuation of this cam post need not be changed at different points in the circular orbit of the cam box. Thus, the jack-actuating cams connected to the posts 396-c or 396-c¹ are changed (raised or lowered) always at the same point in the circular orbit of the cam box.

75 In Figures 65 and 66 two cylinder cam box sections 397 are shown, with the tumblers 390 at the different levels for the different cams which occur in each section.

The dial control is similarly effected as shown in Figure 85 72 to 74 inclusive, by similar tumblers 390, mounted

vertically, at successively different radial distances from the center of the machine and with their control-pins 394 at different levels, so as to be capable of being engaged by the different control cam bars 385. These vertically mounted tumblers 390 shown in Figures 72 to 74 inclusive, are mounted in a dial cam control housing 400, which is mounted on a section of the cylinder cam box 397.

The eccentric pin 395 of each of these vertical tumblers 390 acts as an eccentric pin for a connector rod 401, the adjustable outer end 402 of which is provided with a vertical bearing hole which slips over the eccentric pin 395. The portions 401 and 402 of the connector rod are adjustable, lengthwise, by the threaded sleeve 404 intervening the two members and screw threaded to both by right and left-hand screw threads, so that the turning of the intervening sleeve 404 will effectively lengthen or shorten the distance between the eccentric pin 395 and the down-turned right angular cam-post engaging control arm 405 at the inner end of the connecting rod 401.

To each of the dial cams 406, exemplified in Figure 73 (beneath the dial cap 407), is fastened a tubular post 408 rigidly secured to the cam 406. The tubular post 408 extends upwardly through the dial cap 407, through an elongated and radially disposed slot 409 in the cap 407.

The length of the slot 409 is just sufficient to accommodate the tubular cam-post 408 in each of the two limiting positions of the cam 406. The control arm 405 extends down through the tubular cam-post 408 into proximity of the cam 406 itself, as shown particularly in Figure 73.

By this construction, the connection between the vertical control-tumblers 390 and the cam can be disconnected by merely lifting the connector rods 401 out of position.

For each of the vertical dial-controlling tumblers 390 as shown particularly in Figures 72 to 74 inclusive, a control cam bar 385 is provided. By projecting one or the other of these cam bars 385 inwardly, each tumbler 390, at the level of the particular control cam bar, is caused to revolve 180 degrees from its former position, thereby to change all cams in each of the sections of the dial; each of the tumblers shown in Figures 72 to 74 inclusive being duplicated in each section of the dial.

The stitch control cam-post 410 (Figure 63) has a transverse plate 411 at its upper end, rigidly connected therewith, beneath which the helical compression spring 412 is provided for normally returning the stitch control cam post 410 to its upper position. This post 410 is controlled by the stitch control mechanism 414, shown in Figures 57-58, 63, 71 and 76 to 79.

The stitch control mechanism 414, one of which is provided for each feed of the knitting machine, includes a vertical cam shaft 413 journaled in a vertical bearing in a supporting bracket 414 which is rigidly fastened to the cam box 397. An actuating ratchet wheel 415 is provided near the lower end of the shaft 413, in operative alignment with the stitch control cam bars 384 in the control box, so that by projecting such control bars, the ratchet wheel can be advanced by one tooth or two teeth. By extending one of the two cams bars 384 (Figure 50) the ratchet is turned one tooth, while by extending both of said cam bars, the ratchet is turned by an amount equal to two teeth (namely 60 degrees in the one instance and 120 degrees in the other instance).

The dual-track cam member 416 is provided with a pair of cam tracks 417 and 418, respectively. A pair of lever arms 419 and 420 are pivotally mounted in slotted extension 421 of the bracket 414 as shown particularly in Figures 63, 77 and 79. The inner ends of the levers 419 and 420 carry corresponding cam-follower rollers 423 and 424, pivotally mounted in the forked ends of said levers, each of the two rollers being in registration with one of the two concentric cam tracks 417 and 418. The outer end of each of the levers 419 and 420 is slotted as at 425, and through the slotted outer ends of each lever a pair of screws 426 and 427 are extended, the screws 426 acting as the adjustable post-contacting screws, while the screws 427 acting as locking screws by which the setting of the screws 426 is fixed or locked. The lower ends of the screws 426 bear against the top of the plate 411.

In the particular embodiment of the invention herein shown, cam-tracks 417 and 418 each has two high positions (C-1, F-1 and B-2, E-2) and four low or relieved

positions (A-1, B-1, D-1, E-1 and A-2, C-2, D-2, F-2) with the high positions staggered and with the relief positions overlapping but not coextensive, as shown particularly in Figures 57 and 58. By this means, at least two different stitch-cam adjustments may be obtained by means of the two different levers 419 and 420, because by a different setting of their screws 426, a different amount of depression on the cam post 410 is obtained, according to whether the lever 419 or the lever 420 is being acted upon by its corresponding cam tracks 417 and 418 (one cam track always being relieved at the point where the other cam track has its high point). While in the particular embodiment shown, two high points of each cam track are at the same height, (as for instance, C-1 and F-1 in Figure 57) this may be changed, and these two high points may be slightly different heights. Similarly instead of having a six position cam track, an eight position cam track may be provided with an eight-tooth ratchet wheel, and similarly, more than two tracks may be provided, with a corresponding number of levers.

The upper end of the shaft 413 carries a cam member 428, having two cam tracks, one above the other, but acting in a radial direction, one being 429 the other being 430, each cam track having two high points (C-3, F-3 and A-4, D-4) and four low points (A-3, B-3, D-3, E-3 and B-4, C-4, E-4, F-4), as shown particularly in Figures 57 and 58, the two high points being the outer diameter while the four low points being the relieved portions represented by flats. The angular portions 431 are the inclines on which the cam-followers ride up from the low to the high points. The two high points are diametrically opposed on each of the two cam tracks 429 and 430 and are in staggered relation to each other, while the flat or relieved portions are overlapping, in a manner similar to the relationship of high points and relieved portions of the cam tracks 417 and 418, and being in direct phase therewith, so that the dial stitches and cylinder stitches may be similarly controlled. However, by angularly adjusting the upper cam member 428, a different control may be obtained on the dial stitches than upon the cam stitches, according to the desired stitch formation.

A sliding cam-follower yoke 433 has a forked end 434, which straddles the shaft 413, while the other end thereof slides over the dial cap 407, and is held down against the dial cap by the spring 435, beneath the head 436 of the stud 437, which extends down through a slot in the cap 407, and screw-threadedly engages an aperture or recess 438, in the stitch cam 439.

The cam-follower yoke 433 has a pair of cam-follower screws 440 and 441, adjustably secured in the screw bracket 442 thereof, each of said screws being in alignment with one of the two cam tracks 429 and 430, so that by differently adjusting said two screws, two different adjustable settings of the dial stitch cam 439 may be achieved. The screw bracket or cam-follower bracket 442 is so arranged that the two cam-follower screws 440 and 441 may be locked in position, after they have been set to their desired adjustment. This can be accomplished by slitting as at 444, on one side of the screw threaded hole which receives the screw 440, and extending a locking bolt or screw 445 across the slit, and tightening it, onto the screw 440, after the screw 440 has been set to the desired adjustment. The lower screw 441 may be similarly locked into its adjusted position. A helical tension spring 446 is interposed between the cam-follower yoke 433 and the stationary spring anchorage 447, thereby to hold the cam-follower screws 440 and 441 against their respective cam tracks 429 and 430 and also to hold said yoke 433 into one of the limiting positions of the dial stitch cam 439, namely, when the upper cam member 428 presents a relieved or inoperative portion to both cam-follower screws 440 and 441. The upper cam member is locked to the shaft 413 by means of a split collar, 448, formed integrally with the cam member 428, with split portions tightened by means of the screw 449, in the manner shown particularly in Figures 57, 63, 76, 77 and 78.

A yarn change box 515, at each yarn-feeding station, is carried upon a bracket 590 fastened to the rotating machine body somewhat above the cam-boxes 397, as shown particularly in Figure 71. In the yarn-change box 515 a plurality of yarn-change fingers 460 are piv-

otly mounted about the pivot 461, each drawn back by helical tension spring 462, and each actuated by a sliding cam bar 460-a (Figure 82). A pivotally mounted retainer detent 463, pivoted at 464, serves to keep the yarn fingers in their extended position, by engaging the notch 465, along the lower edge of the corresponding cam bar 460-a; the lever or detent 463 being held in its engaging position by compression spring 466. There is a separate retainer detent or lever 463 for each of the horizontal cam bars 460-a which actuate the yarn fingers 460.

The cam 388 serves to unlatch the retainer detents 463 from their locking position as the yarn-change box 515 moves past the control-stand 382 when the cam 388 is in its extended position.

To the yarn-change box 515, adjacent the yarn-change finger control cam bars 460-a, the scissor mechanism shown in Figures 59 to 62, 83 and 84 inclusive, is secured by means of the screws 467 which pass through the openings 468 in the generally upright supporting member 469 of the scissor mechanism. The member 469 has a forwardly and angularly disposed yarn-clamping portion 470, whose upper edge 471 is slightly beveled, to form a cutting edge or shearing edge 472. The yarn clamping portion 471 is offset in respect to the main body 469, in the manner indicated particularly at 479 in Figures 60, 61 and 62. A pivoted opening 473 extends through the member 470, at approximately the bend thereof. The stationary yarn clamping member 471 is grooved as at 474. The stationary member 475, having a forwardly and downwardly extending bifurcated portion 476, paralleling the stationary yarn clamping and scissor member 470, is rigidly secured to the main body or shank 469 of the scissor mechanism, by means of a pair of screws or bolts 477. The member 475 is also provided with a pivot hole 478, in alignment with the pivot hole 473. The "offset" 479, between the supporting shank 469 and the stationary yarn retaining member 476 and stationary scissor member 471 is equal to the width of the yarn-engaging blade member 480, at the zone 481 thereof, which surrounds the pivotal opening 482 thereof, except for an appropriate working clearance. Thus, when the yarn engaging blade or yarn-depressor 480 is placed between the stationary yarn locking and scissor member 471 and the bifurcated stationary portion 476, in the manner indicated in Figure 59 and in Figure 61, it will substantially take up the space between these members in the pivotal zone thereof, so as to be held firmly therebetween, (while yet permitting it to be pivotally swung up and down). The yarn-depressor or yarn-engaging blade 480 has a rear lever arm 483 with a pivot hole 484 therethrough for the reception of one of the small ends of the pivot 485, whose enlarged center portion is adapted to be received in the pivot hole 486 of the operating link 487, while its other small end is adapted to be received in the pivot hole 488 in the corresponding lever arm 489 of the movable scissor blade 490, having a hole 491 therein in alignment with the pivot holes 473, 482 and 478 (Figure 62).

Between the plain parallel opposed surfaces 492-a and 492-b of the two sides or flanges 476-a and 476-b of the bifurcated member 476, a pair of flat yarn clamping members 493-a and 493-b are slidably mounted, in the manner indicated in Figures 59, 60 and 61, each having its upper inner edge beveled as at 494. Each of the yarn clamping members 493 has a rear recess 495, in its rear edge thereof, as indicated particularly in Figures 59 and 62, which are adapted to receive the U-shaped contact fingers 496 of the springs 497-a and 497-b, respectively, which have the common base plate 498 having a central opening 499, through which is adapted to pass the stem of the headed pivot pin 500, in the manner indicated in Figures 59 and 83. By this means the yarn clamping members 493 are urged yieldably and independently of each other towards the stationary yarn clamping grooves 474 in the manner indicated in Figures 60 and 61. The yarn-engaging or yarn-depressing blade 501 is beveled on its face 502, while its face 503 is offset from, though parallel with, the face 504 of the member 480, by an amount designated by the arrows 505 (in Figure 61), which is equal to or slightly greater than the thickness of the yarn to be handled, so that when the blade 501 engages the yarn and draws it down between the members 470 and 476, the blade 501 will not clamp the yarn between its surface 503 and the grooved face of the member 570, but will leave the yarn

loose between these two surfaces, and confine the yarn-gripping action to its beveled surface 502 and the beveled edges of the slideable yarn-clamping members 493 (Figs. 59 to 62 inclusive). The lower edge 506 of the blade 501 is notched as at 507, with the teeth facing inwardly, so as more securely to engage the yarn when the blade 501 is brought down.

10 A helical compression spring 508 is interposed between the cotter pin 509 (which passes through the cotter pin hole 510 of the pivot pin 590) and the movable scissor-blade 490, so as yieldably to urge the cutting edge 511 of movable scissor blade 490 towards the stationary scissor blade 472, when the yarn clamping and scissor mechanism are operated.

15 The upper-link pivot-hole 512 of the operating link 487 of the yarn clamping and scissor mechanism shown in Figures 59, 62, 80 and 84 is connected to the rocker arm or bell crank arm 513, which is pivoted upon the pivot 514 (Figures 71 and 80) upon the control box portion 515 which carries the yarn-changing cam bars 460-a. The upper arm 516 of the bell crank member 513 is bifurcated as at 519, and into its forked end 519 the operating pin 520, carried by the scissor-control cam-bar 521, extends. Thus, by advancing the scissor-control cam-bar 521, by 20 the appropriate placement of the cam 388 and a selector-jack 252, the yarn cutting scissor and yarn clamping mechanism are actuated. This, of course, is done in timed relation to the actuation of the yarn-change fingers 460, by their corresponding cam bars 460-a.

25 The pin 522, carried by the stationary bifurcated member 476, serves to keep the out-stretched yarn to the front portion or front half of the yarn-clamping blade 501 and to the front half of the scissor blade 490, so as to insure proper clamping and cutting.

30 The cutting edge 511 of the scissor blade 490 is sufficiently behind or above the clamping edge 506 of the clamping blade 501, that the clamping action is firmly established between the beveled face 502 of the blade 501 and the beveled edges of the slideable clamping members 593, before the cutting action between the edges 511 and 472 takes place, so that the cut end of the yarn (leading to the bobbin) is firmly clamped before it is cut from the end of the yarn which goes to the knitted fabric. As the clamping blade 501 is then withdrawn, it leaves a 35 loop of yarn behind, which loop of yarn is then clamped between the beveled edges of the members 493 and the grooves 474.

35 Thus, whenever a yarn-change finger 460 is released (by the unlatching of the detent lever 463 from the cam bar thereof) so as to swing into its inoperative position (shown in solid lines in Figure 83), the yarn passing through its apertured pay-out end or eyelet is moved across the open mouth of the scissor and yarn clamping mechanism, so as to be brought between the stationary members 471 and 476 thereof and the upper movable blades 501 and 490 thereof, up to the pin 522. This is then followed by the actuation of the yarn clamping and scissor mechanism, which first clamps and then cuts the yarn which has been so retracted from the knitting operation. When the yarn finger is advanced forwardly again to bring it in to the knitting zone, the so advanced yarn change finger 460 carries the yarn (with its cut end still clamped in the clamping mechanism) into the needles, where it is engaged by the needles and as the yarn is carried around the needles, it is torn loose from the yarn-clamp mechanism.

40 The fabric-takeup-mechanism, as shown particularly in Figures 85 and 86, is operated from the cam or eccentric 530, upon the main cam-shaft 191 (Figures 27 and 28), 45 which is disposed between the forked end 531-a and 531-b of the lever arm 531, which lever-arm is pivoted upon the pivot 532; the forked ends 531-a and 531-b acting as a cam-follower. To the arm or lever 531, the link 533 is pivotally secured by the pivot 534. To the link 533 the connector rod 535 is adjustably secured by means of a threaded end 536, held in adjusted position by the lock nut 537; the threaded end 536 being threaded into a 50 correspondingly threaded hole in the link member 533.

55 The connecting rod 535 extends downwardly and terminates in a pivot link member 538, which is similarly adjustably secured to the lower end of the rod 535, and is, in turn, pivoted by the pivot bolt 539, to the arm 540 of the bell-crank lever 541, which is pivoted upon the 60 pivot pin 542 carried by the stationary pivot supports 543.

extending upwardly from the base frame member 544. The more-or-less right angular lower arm 541, of the bell-crank lever 541, carries a lateral pin 546, at its lower end, which pin extends into the vertical slot 547 in the oscillating slide bar 548, which is guided in a horizontal line by the members 549 and 550, which extend upwardly from the base frame member 544, and form, between them, guideways for guiding the slide bar 548, as it is oscillated to and fro, by the oscillating pin 546 of the bell-crank lever 541.

The oscillating bar 548 carries a pin 553, upon which is journaled the guide-block 554, which, in turn, is slidably mounted between the bifurcated end 555 which forms one end of the rocker arm 556, loosely pivoted upon the shaft 557. The pin 546, may be similarly surrounded by a guide block (similar to the guide block 554) which, in turn, is slidably mounted in the slot 547, so as to get a better bearing between the actuating pin 546, and the side walls of the slot.

By this means, with each rotation of the main cam shaft 191, the slide bar 548 is oscillated to-and-fro, once, and the rocker arm 556 is similarly oscillated to-and-fro, once. The upper end 559 of the rocker arm 556 has an actuating pawl 560 pivotally secured thereto at 561, in operative alignment with the ratchet wheel 562 which is keyed to the shaft 557. To the shaft 557 the main take-up roll 563 is also keyed; the roll 563 being knurled or otherwise roughened to provide a firm fabric-gripping surface. Thus, as the bar 548 rocks back and forth, in a horizontal direction, the pawl 560 is caused to oscillate to-and-fro over the toothed periphery of the ratchet wheel 562. The main take-up shaft 556 is journaled in a pair of opposite and similar pivotally mounted arms 564 (only one of which is shown), which are pivoted upon the pivot shaft 565, which in turn is carried in the bearing brackets 566 (only one of which is shown). The two lever arms 564 are further interconnected by the stationary bar 567, so as rigidly to interconnect the two arms 564 at the opposite ends from the take-up rolls 563, 568 and 569. To an extension 570, on one of the two lever arms 564, a check-pawl 571, or two or three adjacent and similar check-pawls 571 (as shown particularly in Figure 85) are pivotally mounted upon the pivot pin 572, so that when the driving pawl 560 has advanced the notched ratchet wheel 562 the distance of a tooth or a distance equal to a fractional distance of a tooth, the check-pawls 571 will keep the ratchet wheel 562 and the take-up roll 563 in its so-advanced position. The pawl point or tooth of each of the several check-pawls 571 are slightly differently spaced, so that one of them will fall behind the tooth even though it is advanced a distance less than a tooth.

The knitted fabric 573 issuing from the banks of knitting needles, above, enters downwardly between the rolls 563 and 568, passes around the underside of roll 563 and upwardly again between the roll 563 and the roll 569 and then down over the roll 569 and then downwardly again, where it may be taken up on a roll or just left resting in a heap.

As the pair of opposed lever arms 564, which carry the three rolls 563, 568 and 569 are free to oscillate up and down about their pivot shaft 565, the take-up rolls will ride upon the cloth under the influence of the ratcheting-advance caused by the movement of the pawl 560, and in so doing will gradually raise the shaft 557, so that the pivot pin 553 will be further and further away from the center of the shaft 557 and thus effectively lengthen the lower arm of the rocker 556 and thereby decrease the angle through which the pawl 560 oscillates. Thus, as the take-up mechanism rides up on the fabric, the ratchet becomes ineffective because the pawl 560 will not oscillate the distance of one tooth but simply oscillate to-and-fro on the same tooth. However, as more cloth issues from the knitting operation, and the shaft 557 is thus lowered, the distance between the shaft 557 and the pin 553 is so reduced as to increase the angular traverse of the pawl 560 until it falls behind the next tooth and thus again advances the ratchet wheel 562 and the main feed roll 563. In this manner, an automatic take-up adjustment is effected, in which the weight of the rolls and of the arms 564 (counterbalanced only the spring 574) serve to give a constant tension upon the knitted fabric, and insures that this tension will be maintained at all times without any accidental slack on the fabric.

The roll 568 is journaled in a bearing block carried in the slot 575 in the ends of the lever arms 564, and may be spring pressed towards the main feed roll 563 by suitable springs urging its bearing block towards the roll 563 (the bearing blocks in which the shaft of the roll 568 is journaled being slidably mounted in the slots 575 in the lever arm 564), or the roll 568 may be positioned in the slot 575 by set-screws, or the like, to hold the shaft of roll 568 more-or-less unyieldingly in place on the slot 575.

The shaft 577, which carried the take-up roll 569 is journaled in a pair of opposed bearing blocks which are slidably mounted in the forked end 578 of a pair of similar lever arms 579 (only one of which is shown in the drawings), said lever arms, being in turn, pivoted upon the pivot shaft 565. The bearing blocks in which the ends of the shaft 577 are journaled are spring urged towards the main take-up roll 563. One or both of the lever arms 578 carries an upward extension 579, through which a pivot 580 is extended. A bell-crank shaped member 581 is pivoted to the member 579, by means of the pivot pin 582. The lower portion 583 of the bell-crank member 581 extends into vertical alignment with the lever arm 564, so as to rest thereon when the bell-crank lever is in the position shown in Figure 86. By raising the handle portion 584 of the bell-crank member 581, the lever arm 579 may be lowered in respect to the lever arm 564, thereby to permit the take-up roll 569 to fall beneath and away from the main take-up roll 563, so as to form a clearance between these two rolls and to render the roll 569 inoperative. This is desired in order to permit the manipulation of the fabric between the take-up rolls and also to render the take-up roll 569 inoperative for any other reason. By depressing the arm or arms 584, the lower camming portion 583 of the rocker arm or arms 581 is forced to ride up on the lever arm or arms 564, thereby elevating roll 569 in relation to the roll 563, and thereby bringing the roll 569 into juxtaposition with the roll 563.

The adjustable spring-anchorage rod 585 is provided on one or both of the lever arms 564, in the manner shown in Figures 85 and 86, being adjustably secured thereto by the set screw 586. The lower end of the spring or springs 574 are, in turn, secured to an adjustable stationary spring-anchorage 587, as shown in Figure 1, which is adjustably secured to the downwardly extending post 588.

A hand wheel 489, shown in dotted lines in Figure 85, may be secured to one end of the main shaft 557 of the take-up mechanism, whereby the take-up may be advanced manually for its initial setting, or for any other reason.

Having described our invention, we claim the following:

1. In a knitting machine, a selector-chain operating mechanism, including a selector-chain drum carrying a selector chain and adapted to be advanced stepwise by uniform angles, to advance successive links of the selector-chain thereon into operative juxtaposition to the cam-actuating selector bars which are adapted to be actuated by the selector-chain, said mechanism including a lifting cam and a follower operatively associated therewith for raising said selector-chain drum against said selector bars, a timing chain, and means intermediate said timing chain and said lifting cam, for shifting said lifting cam into and out of operative relation to said cam follower.

2. In a knitting machine a selector-chain operating mechanism including a cam shaft having a lifting cam thereon adapted to lift the selector-chain drum, cam-follower means intermediate said cam and said selector-chain drum for causing the former to actuate the latter when said follower and said cam are in operative relation to each other, a timing shaft driven in timed relation to said cam shaft, a timing chain driven by said timing shaft and having operative links and inoperative links, means cooperating with said timing chain and adapted to be engaged by the operative links thereof to bring said lifting cam and the follower thereof into operative relation to each other; said lifting cam and the follower thereof being normally kept in an inoperative relation to each other except when under the influence of an operative link of said timing chain.

3. In a knitting machine having selector-transmission means, timing means and a selector chain in operative

juxtaposition to said selector-transmission means, a control shaft, a selector-eccentric carried by said control shaft arranged operatively to raise said selector-chain against said selector-transmission means, means intermediate said selector-eccentric and said timing means for rendering said selector-eccentric operative, responsive to the settings of said timing means, and an intermittent drive between said control shaft and said timing means for intermittently advancing the latter in predetermined ratio to the former, said drive being positively locking when said timing means is not driven, thereby to prevent said timing means from being moved except responsive to said drive and except in the ratio aforesaid.

4. In a knitting machine having a control shaft and a timing shaft and having a selector-chain drum and a selector-chain carried by and intergeared with said drum, an axially shiftable selector-eccentric upon said control shaft, and interconnection between said selector-eccentric and said selector-chain drum for permitting the former operatively to move the latter, an intermittent drive between said control shaft and said timing shaft for intermittently rotating the latter fractions of a revolution for a suitable number of revolutions of the control-shaft and for keeping the timing shaft positively interlocked in relation to the control shaft at all times so that it may not be rotated independently of the control-shaft, adjustable timing means operatively connected to said timing shaft, said adjustable timing means having movable members secured in selected positions thereto, according to the timing desired, and eccentric-shifting means intermediate said timing means and said selector-eccentric, for shifting the latter into its operative position, and means for retaining said selector-eccentric in an inoperative position when not acted upon by said timing means.

5. In a circular knitting machine having a control-shaft and a timing-shaft and a selector-chain carrying drum and a selector-chain carried thereby and intergeared therewith, a laterally shiftable selector-eccentric carried by said control-shaft and keyed thereto, selector-drum actuating means intermediate said selector-eccentric and said selector-chain drum for permitting the former operatively to move the latter, said selector-eccentric being capable of being shifted into either of two positions upon said control-shaft, namely into an inoperative position in which it will not move said selector-chain drum and into an operative position in which it will move said selector-chain drum, a shifting-cam on said control-shaft and connected to said eccentric, said shifting-cam having an axially operative cam-track, and an intermittent and constantly interlocking drive between said control-shaft and said timing-shaft for intermittently driving the latter through fractions of a revolution for a suitable number of revolutions of the control-shaft, said drive positively interlocking the timing-shaft in relation to the control-shaft at all times, a sprocket-wheel carried by said timing-shaft, a timing chain upon said sprocket-wheel, a timing-cam adjustably carried by said timing-chain, a cam-follower in operative juxtaposition to said timing-chain, and means intermediate said cam-follower and said shifting-cam and co-acting with the cam-track thereof, for causing said shifting-cam to shift said selector-eccentric into its active position when said timing-cam upon said timing chain is moved into operative juxtaposition to said cam-follower and means urging said shifting cam into an inoperative position when said timing-cam is not in operative juxtaposition to said cam-follower.

6. In a circular knitting machine having a control-shaft and a timing-shaft and having a selector-chain drum and a selector chain carried thereby, a selector-eccentric carried by and keyed to said control-shaft and being mounted thereon to be capable of shifting axially thereon, follower-arm mounted in operative juxtaposition to said selector-eccentric in one of its two positions into which it may be shifted along said control-shaft, said follower-arm being operatively connected with said selector-chain drum so as to raise the same through an operative stroke thereof whenever the selector-eccentric is shifted into alignment with said eccentric-follower, a shifting-cam mounted upon said control-shaft and connected with said selector eccentric, for shifting the latter into either one of its two positions, namely to its operative or inoperative position, respectively, said shifting-cam having a pair of opposed axially-directed cam-tracks,

a timing-cam lug mounted upon said timing-shaft and disposed thereon to travel around said timing-shaft, a cam-shifting arm in operative juxtaposition to said shifting-cam and having a pair of opposed cam-followers arranged alternately to align with said shifting-cam thereby alternately to engage one or the other of the cam-tracks thereof, thereby to cause said shifting-cam to shift into either one of its two positions under the influence of said shifting-arm, and means intermediate said cam-shifting-arm and said timing-cam lug, causing said shifting arm to move into its selector-activating position under the influence of said timing-cam lug.

7. In a circular machine having a control-shaft and a timing-shaft, a timing-shaft driving mechanism including a pair of similar driven star-wheels mounted upon said timing-shaft, adjacent each other, one keyed to said timing-shaft and the other mounted thereon to be rotatable in relation thereto, each star-wheel having generally radial drive-slots and concave peripheral locking portions intermediate said slots, a cam also idly mounted upon said timing-shaft and connected with the latter of the two star-wheels, and having an axially directed cam-track with a relatively short axially shifting dwell, an axially shiftable intermediate rotary driving and locking member rotatably mounted intermediate said control-shaft and said timing-shaft and having a pinion in constant mesh with a pinion on and keyed to the control-shaft and having a full-circular wheel-locking portion adapted to interlock with the convex peripheral locking portions of said keyed star-wheel when shifted into one of its two positions and to clear of said keyed star-wheel when shifted into the other of its two positions, and having a part-circular wheel-locking portion adjacent to and rigidly connected with said full-circular wheel-locking portion and having a peripheral wheel-clearance thereon, and a lateral eccentric slot-engaging driving pin carried by said rotary driving and locking member opposite to said wheel-clearance, a cam carried by said rotary driving and locking member for shifting the same, and means interconnecting the first-mentioned cam with the last-mentioned cam for causing the latter to shift into its driving position whenever the shifting-dwell of the first-mentioned cam actuates said cam-interconnecting means.

8. In a knitting machine having a selector chain including a pair of parallel chain links and pivot rods therebetween, a selector jack adapted to be detachably and adjustably secured to a pair of adjacent pivot rods on said selector chain, said selector jack including a base member adapted to be disposed beneath a pair of pivot rods, a selector knob extending upwardly from said base member generally at a right angle thereto, a pivot rod receiving recess on one side of said knob and formed between said knob and a locking flange extending upwardly from said base member, another pivot rod receiving recess on the other side of said knob formed between said knob and said base member, a lateral hole extending through said knob and another hole extending through said flange in alignment with said lateral hole, at least one of said holes being screw-threaded, and a headed screw extending through said two holes and adapted to extend over a pair of pivot rods flanking said knob, with its head in said other recess wedging engaging one of said pivot rods.

9. In a circular interlock knitting machine, a selector chain mechanism including a chain-carrying drum of polygonal cross-section having flat jack-supporting faces, a ratchet wheel affixed to said drum, timed means for periodically reciprocating said drum, with its axis remaining parallel and in generally the same plane, a ratchet wheel advancing pawl in operative juxtaposition to said ratchet wheel for advancing said drum by one face thereof upon each return motion of said drum in its aforesaid reciprocation, said selector chain mechanism having selector jacks adjustably secured to the selector chain, said selector jacks having basal surfaces matching the faces of said drum and to rest thereon in their operative positions.

10. In a knitting machine having a control stand containing a plurality of selector-transmission members adapted to be displaced by a selector-chain, a selector-chain drum, a selector-chain carried thereby, a control-shaft, a selector eccentric carried by said control-shaft for moving said selector-chain against said selector-transmission members, thereby to displace the selected ones of such members into their operative positions, a return eccentric carried by said control-shaft and means inter-

mediate said return eccentric and said selector-transmission members for returning the latter from their operative positions to their inoperative positions.
